US0D1038116S

(12) **United States Design Patent** (10) **Patent No.:** **US D1,038,116 S**
(45) **Date of Patent:** **** Aug. 6, 2024**

(54) **NOTEBOOK COMPUTER**

(71) Applicant: **Samsung Electronics Co., Ltd.**, Suwon-si (KR)

(72) Inventors: **Sungjin Yum**, Suwon-si (KR); **Iksang Kim**, Suwon-si (KR)

(73) Assignee: **SAMSUNG ELECTRONICS CO., LTD.**, Gyeonggi-Do (KR)

(**) Term: **15 Years**

(21) Appl. No.: **29/832,814**

(22) Filed: **Mar. 30, 2022**

(30) **Foreign Application Priority Data**

Dec. 2, 2021 (KR) 30-2021-0057993

(51) **LOC (14) Cl.** **14-02**

(52) **U.S. Cl.**

USPC **D14/327**; D14/315

(58) **Field of Classification Search**

USPC D14/315-327, 341, 345, 439-440, 447; D18/1-3.1, 4.1-4.6, 12.1-12.3; D21/324,

D21/329-330, 332, 515

CPC G06F 1/1616; G06F 1/1633; G06F 1/1656

See application file for complete search history.

(57) **CLAIM**

The ornamental design for a notebook computer, as shown and described.

DESCRIPTION

FIG. 1 is a top perspective view of a notebook computer, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines illustrating portions of the notebook computer form no part of the claimed design.

1 Claim, 3 Drawing Sheets
